CLAIM

The ornamental design for a bank note sorting, counting and bundling machine, as shown and described.

DESCRIPTION

FIG. 1 is a front, top right perspective view of a bank note sorting, counting and bundling machine showing my new design, with the outlets shown in an open position;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and

FIG. 7 is a bottom plan view thereof.

FIG. 1

FIG. 2

FIG.3

FIG.5

FIG.4

FIG.6

FIG.7
